UNITED STATES PATENT OFFICE.

PETER FRANTZ, OF STERLING, ILLINOIS, ASSIGNOR TO FRANTZ MANUFACTURING CO., OF STERLING, ILLINOIS, A CORPORATION OF ILLINOIS.

DOOR-HANGER.

1,195,197.

Specification of Letters Patent. Patented Aug. 22, 1916.

Application filed January 21, 1915. Serial No. 3,463.

To all whom it may concern:

Be it known that I, PETER FRANTZ, a citizen of the United States of America, and resident of Sterling, Whiteside county, Illinois, (residential address 309 Ninth avenue,) have invented a certain new and useful Improvement in Door-Hangers, of which the following is a specification.

My invention relates to door hangers of that kind in which a wheeled body is arranged to travel on a track for supporting the door.

One object of my invention is to provide an improved construction and arrangement for adjusting the door up and down on the hanger.

Another object is to provide a hanger in which are combined the said feature of vertical adjustment and means for securing the hanger to the inside of the door, and in which a hinge connection is interposed between the wheeled body and the said adjusting means, the construction being such that the raising and lowering of the door, by the adjustment of screw threaded means inside thereof, does not vary the position of the hinge of said connection.

It is also an object to provide certain details and features of construction and combinations tending to increase the general efficiency and desirability of a door hanger of this particular character.

To the foregoing and other useful ends my invention consists in matters hereinafter set forth and claimed.

In the accompanying drawings—Figure 1 is a side elevation of a door hanger embodying the principles of my invention, viewed from the inside thereof, showing a portion of the door to which the attaching and adjusting means are secured. Fig. 2 is an end elevation of the said hanger. Fig. 3 is a vertical section on line 3—3 in Fig. 1, on a larger scale, showing the track and the side of the building in dotted lines. Fig. 4 is a perspective, on a still larger scale, of the upper portion of the bolt by which the door is supported for vertical adjustment, and the head of which bolt is formed to provide not only the pintle for the hinge, but also the shoulder which co-operates with a shoulder on the hanger to limit the hinge motion in one direction, whereby the door and the wheeled body can swing outward relative to each other but not inward from the normal position thereof.

As thus illustrated, my invention comprises a body A provided at each end thereof with wheels a arranged to travel on a track of any suitable character, such as the track B indicated in Fig. 3, and having a depending portion C which is bent around the inner edge of the track at c, and which is provided with an upturned or hook shaped portion c¹ at its lower end, the slot 65 or notch c² dividing said portion into two parts, and giving the lower end of said portion C a bifurcated character. The portion C is secured at its upper end by a bolt a¹ inserted through the body. A vertically disposed bolt D is provided at its upper end with a cylindrical head or cross piece d which rests in the bearing formed by the portion c¹, thereby forming a hinge having a horizontal axis disposed directly below the tread of the wheels, said axis extending parallel with the upper edge of the door. The head of this bolt is also provided with a shoulder d¹ which engages the end or upper edge of the notch c², as shown in Fig. 3, 80 whereby the hinge motion is limited in one direction to prevent the door and wheeled body from swinging toward the building relative to each other, from their normal or upright positions. As shown, the bolt D 85 extends downward and swings in the notch c², and said pintle d is removable with the bolt in an upward and outward direction from the portion c¹ which forms the supporting bearing for the hinge. The door E 90 is recessed at e and e¹, as shown in Fig. 3, and the bolt D extends downward through that portion of the door which is disposed between said recesses, the latter being formed on the inner surface of the door. A 95 bracket plate F is provided with parallel and horizontal ears f and f¹, at the upper and lower ends thereof, these ears being inserted respectively in the recesses e¹ and e and embracing the portion of the door between said recesses. These ears f and f¹ are perforated to receive the bolt D, and the said bracket F and the door carried thereby are supported by a nut G which engages the underside of the ear f¹, and which is 100 screwed on to the lower screw threaded portion of the bolt D, whereby the door can be raised and lowered by the rotary adjust-

ment of said nut. The pintle *d* holds the bolt *D* against rotation when the nut *G* is rotated. As shown in the drawings, the door has been adjusted upward until the ear 5 *f* is in contact with the head of the bolt *D*, whereby the door is not adjustable any higher; but from this position the door can be lowered considerably, by screwing the nut *G* downward, and it will be understood 10 that the proper adjustment of the door is determined by the conditions and circumstances of each case.

Any suitable means can be employed for securing the bracket plate *F* to the door. 15 As shown, horizontal bolts *H* are inserted outwardly through said plate, through the door, and through a plate *h* in the outer surface of the door. These bolts *H* are provided at their outer ends with nuts *h*¹, and 20 the inner heads of the bolts are, it will be seen, countersunk in the bracket plate, whereby the inner surface of the door is practically flush. It will be seen that the two bolts *H* are arranged at opposite sides 25 of the bolt *D* and disposed in the same horizontal plane.

With the foregoing construction, it will be seen that the door is not only supported for vertical adjustment thereof, but that this 30 adjustment is, furthermore, effected by means arranged inside of the door. With the adjusting mechanism thus protected from the weather, an easy adjustment is insured at all times as the nut will not rust 35 tight on the bolt. Moreover, these advantages are all combined in a hanger which has a hinge connection between the door and the traveling hanger, inside the track, this hinging arrangement being desirable 40 for various well known reasons, and being accomplished by utilizing the upper end of the adjusting bolt as a pintle for the hinge. Thus everything is inside of the track and 45 the door.

I do not limit myself to the exact construction shown and described.

What I claim as my invention is:—

1. A door hanger comprising a wheeled body arranged to travel on a track for supporting the door, having a hinge formed with a stop to limit the hinge motion in one direction, adjusting means inside of the door to raise and lower the latter relative to said hinge and body, and a connection entirely inside of said track to support the hinge on said body, said means including a vertical bolt, a door-supporting member movable up and down on said bolt, and a nut screwed on 50 said bolt to engage the bottom of said member.

2. A door hanger comprising a wheeled body arranged to travel on a track for supporting the door, having a hinge formed with a stop to limit the hinge motion in one 55 direction, adjusting means inside of the door

to raise and lower the latter relative to said hinge and body, and a connection entirely inside of said track to support the hinge on said body, said means including a vertical bolt extending downward into the door between the inner and outer sides thereof, and a nut on the lower end of said bolt to raise and lower the door. 70

3. A door hanger comprising a wheeled body arranged to travel on a track for supporting the door, and adjusting means inside of the door to raise and lower the latter relative to said body, said means including a bolt extending downward into the door, a bracket plate slidable on said bolt and 75 formed with top and bottom ears embedded in the door, bolts inserted through the door and plate at opposite sides of said bolt to hold the plate in place, and a nut screwed upon the lower end of said bolt to engage 80 the bottom ear of said plate, said door having recesses for the upper and lower ends of said supporting bolt. 85

4. A door-hanger comprising a wheeled body arranged to travel on a track to support the door, and a hinge connection between the door and said body, said connection including a bolt secured to the door, a slotted bearing depending from said body, a pintle resting horizontally in said bearing, 90 said pintle forming the head of said bolt, and said head having a shoulder extending into said slot to engage the end thereof and thereby limit the hinge motion in one direction. 95

5. A door-hanger comprising a wheeled body arranged to travel on a track to support the door, and a hinge connection between the door and said body, said connection including a bolt secured to the door, a slotted bearing depending from said body, a 100 pintle resting horizontally in said bearing, said pintle forming the head of said bolt, and said head having a shoulder extending into said slot to engage the end thereof and thereby limit the hinge motion in one direction, 105 said pintle being directly below the wheel-tread, and said shoulder being inside of said pintle. 110

6. A door-hanger comprising a wheeled body arranged to travel on a track to support the door, and a hinge connection between the door and said body, said connection including a bolt secured to the door, a slotted bearing depending from said body, 115 a pintle resting horizontally in said bearing, said pintle forming the head of said bolt, and said head having a shoulder extending into said slot to engage the end thereof and thereby limit the hinge motion in one direction, 120 said pintle being removable upwardly and outwardly from said bearing. 125

7. A door-hanger comprising a wheeled body arranged to travel on a track to support the door, and a hinge connection be- 130

tween the door and said body, said connection including a bolt secured to the door, a slotted bearing depending from said body, a pintle resting horizontally in said bearing, 5 said pintle forming the head of said bolt, and said head having a shoulder extending into said slot to engage the end thereof and thereby limit the hinge motion in one direc-

tion, said bolt having a nut for raising and lowering the door.
